UNITED STATES PATENT OFFICE.

JAMES G. McNAMARA, OF BROOKLYN, NEW YORK, ASSIGNOR TO MERGENTHALER LINOTYPE COMPANY, A CORPORATION OF NEW YORK.

TYPOGRAPHICAL MACHINE.

Application filed May 19, 1924. Serial No. 714,214.

This invention relates to typographical machines, such as linotype machines of the general organization represented in the Mergenthaler Patent No. 436,532, wherein 5 circulating matrices are released from a machine by suitable escapement devices in the order in which their characters are to appear in print, and then assembled in line, the composed line transferred to the face of a mold, the mold filled with molten metal to form a slug or linotype against the matrices which produce the type characters thereon, and the matrices thereafter elevated and returned through distributing mechanism to 10 the magazine from which they started. More particularly, it relates to that class of machines equipped with a plurality of magazines mounted in a so-called shift frame, which is movable rectilinearly to 15 bring any selected magazine into operative relation to the assembling and distributing devices. In the commercial machines, the magazines are supported in parallel spaced relation upon separate base frames pivoted 20 at their upper ends and resting upon one another at their lower ends, means being provided for spreading the base frames apart to permit the independent removal of 25 the magazines.

30 The present invention is directed to certain improvements in machines of the class stated and contemplates a construction which will permit the ready removal of the magazines, and this without having to spread them apart prior to removal. The exact nature of the improvements will best be understood from the detailed description to follow.

Referring to the drawings:—

40 Fig. 1 is a side elevation of the upper portion of a linotype machine equipped with the present improvements, the dotted line position showing the magazines elevated for front removal;

45 Fig. 2 is a plan view of one of the base frames and the associated parts;

Fig. 3 is a detail perspective of the escapement bar; and

50 Fig. 4 is an enlarged vertical section taken through the magazine structure and showing three positions of the means employed to permit the removal of escapement bar and magazine.

The matrices X are stored according to font in the superposed channelled magazines A, three of which are shown herein, but of which a greater number might be employed, if desired. The several magazines A are mounted upon separate base frames A¹ carried by a bottom supporting frame A³, which 55 is arranged to be moved upwardly and downwardly to bring any selected magazine into operative relation to the assembler entrance B and magazine entrance F¹, the latter leading from the distributor F. Each 60 of the magazines A is provided with matrix releasing escapements e, which, when the magazine is in use, are actuated through the medium of pivoted levers C¹ by reeds C², controlled in the usual way from a keyboard (not shown). The escapements of 65 each magazine are, as usual, mounted in a supporting bar or frame C (Fig. 3), which may be engaged with or disengaged from the magazine at will. The supporting 70 frame A³ is attached to a sliding plunger L (see Fig. 1), adapted to be raised and lowered within a fixed sleeve O by the well-known screw thread mechanism usually employed in machines of this character. In 75 order to guide the magazine supporting frame A³ in its rectilinear movements, it is provided with the perpendicular members A⁴, arranged on opposite sides and near the upper end thereof, and having sliding engagement with supplementary brackets O², secured to the inner faces of the main distributor bracket O¹. Registering and locating means for the magazines are also 80 provided, such means comprising (see Fig. 90 1) a pair of bars D¹, movably arranged on opposite sides of the machine and adapted to cooperate with lugs D protruding from the sides of each of the base frames A¹. These bars are loosely connected to the upper 95 ends of a pair of arms D², fastened to a rock shaft D³, which is actuated from the front of the machine against the tension of a spring D⁴, the latter tending to keep the bars in their active positions. The parts so 100 far described, except as hereinafter pointed out, are or may be the same as those embodied in the commercial Model 8 linotype, or as shown and described in the Rogers Patent No. 1,109,872, to which reference may 105 be had, if desired.

According to the present invention, the magazine base frames A^1 are secured to the bottom supporting frame A^3 by clamping bolts a , which pass through spacing blocks A^5 or gauge pieces A^5, A^6 , protruding from opposite sides of said frames at their upper and lower ends. The proper positioning of the base frames is taken care of by means of two pairs of set screws a^1, a^2 , the former arranged in the perpendicular members A^4 and extending inwardly therefrom to engage the side faces of said frames, and the latter passing through the gauge pieces A^6 and engaging the rear edges of said perpendicular members (Fig. 2.) In this way, the base frames are made capable of independent adjustment, both laterally and longitudinally, before they are fastened down upon the bottom supporting frame A^3 , the bolt apertures in the spacing blocks A^5, A^6 being sufficiently enlarged for the purpose. A rigid composite shift frame comprising a bottom supporting frame and a plurality of subsidiary magazine frames is thus provided, although as will later be seen, the magazines are capable of being removed independently in the desired manner. It may also be noted that the construction is such that the shift frame may be built up to accommodate any desired number of magazines simply by the employment of the requisite number of base frames.

Since the magazine shift frame is in the nature of a rigid structure, the locating bars D^1 are made capable of vertical adjustment, in order to insure registration of the magazines with the assembling and distributing devices. Accordingly, the bars are mounted in adjustable front and rear brackets O^3 and O^4 . Set screws O^5 serve as a vertical support for the rear brackets O^4 and clamping screws O^6 serve to fasten them in place against the inner faces of the distributor bracket O^1 . The front brackets O^3 are similarly provided with supporting set screws O^7 and clamping screws O^8 .

It has been the common practice in machines of this class either to pivot the escapement bars to the base frames, so that they may be lowered out of the way to facilitate the removal of the magazines, or to mount them in the shift frame in some such manner as shown in the Rogers patent before mentioned. In the present instance, however, the escapement bars are mounted upon and carried by the base frames A^1 and in such manner that they may be removed endwise therefrom preparatory to the removal of the magazines. Accordingly, the base frames A^1 are provided with plates A^7 fastened to and extending forwardly from the underside thereof to support the escapement bars, the latter being held in place by tongue and groove connec-

tions A^8, A^9 , which permit their ready endwise removal. In order to facilitate such removal of the escapement bars, means are provided for first breaking the operative engagement between them and the magazines. To this end, each base frame is provided with a hinged member G , formed at its lower end with a lip portion G^1 , which engages the lower cross rib of the magazine and retains the latter in place upon the base frame. This retaining member is adapted to be swung upwardly to raise the magazine by means of a transverse shaft G^2 , journalled in the base frame and provided at one end with a small hand crank G^3 . As shown, the rock shaft is cut away or recessed as at g, g' to receive and support the retaining member at two different lower levels. With this arrangement, it will be seen that by turning the associated hand crank G^3 , any magazine may be raised clear of the corresponding escapement bar to allow the latter to be withdrawn endwise in the manner stated (see Figs. 2 and 4.)

As illustrated in Fig. 4, the customary removable rod P is employed to lock the matrices in the magazine before its disengagement from the escapement bar. In the present instance, the rod is also employed, when shifted from its position within the magazine to that shown in the drawings, to lock the magazine retaining member G against upward movement. In other words, the escapement bar is grooved, as at E , to receive the rod P , in such position that the latter engages the end of the member G and thereby prevents rotation of the rock shaft G^2 and the consequent raising of the magazine. In this way, the premature disengagement of the magazine from the escapement bar is prevented.

The manner in which the magazines are removed will now be clear: In Fig. 4, the rock shafts G^2 and the magazine retaining members G are shown in three different positions, designated x, y and z , respectively. When a rock shaft is turned from position x to position y by means of its small hand crank G^3 , the member G is cammed upwardly far enough to raise the magazine clear of the escapement bar C , which latter (shown in dotted lines) is then free to be removed endwise in the desired manner. When the rock shaft is later turned from position y to position z , the member G drops into the recess g and carries its retaining lip G^1 out of the way of the magazine, which may then be slid forwardly in its own plane from the base frame for removal. A pair of supporting arms R (see dotted lines, Fig. 1) may be employed to assist the operator in removing the magazine and substituting another. After a substituted magazine has been placed upon the base frame, the rock shaft is turned back to position y and lifts

the retaining member G into engagement with the magazine. The escapement bar C is then reinserted and pushed home against an adjustable stop A¹⁰ (Fig. 2). The rock shaft is thereafter turned to its original position α and brings its recess g' into position to receive the member G, thus permitting the magazine to be lowered into operative engagement with the escapement bar. If desired, the escapement bar may be provided, for registration purposes, with the ordinary locating tooth α (Fig. 3), which is adapted to engage a corresponding notch in the magazine. The matrix locking rod P may now be withdrawn with safety from the magazine and reinserted in the escapement bar to function in the manner before described.

In the accompanying drawings, the improvements have been shown merely in preferred form and by way of example and, obviously, many changes and variations may be made therein and in their mode of application, which will still be comprised within the spirit of the invention. Generally speaking, the invention is not limited to any specific form or embodiment, except in so far as such limitations are specified in the claims.

Having thus described my invention, its construction and mode of operation, what I claim and desire to secure by Letters Patent of the United States, is as follows:

1. In a typographical machine, the combination of a matrix magazine, a base frame upon which the magazine is removably mounted, and an escapement bar carried by the base frame in operative engagement with the magazine, the said bar being capable of endwise removal to permit the removal of the magazine in its own plane.

2. In a typographical machine, the combination of a matrix magazine, a base frame upon which the magazine is removably mounted, an endwise removable escapement bar carried by said base frame in operative engagement with the magazine, and means for breaking such engagement to permit the endwise removal of said escapement bar.

3. In a typographical machine, the combination of a matrix magazine, a base frame upon which the magazine is removably mounted, an endwise removable escapement bar carried by said base frame in operative engagement with the magazine, means for separating the magazine and escapement bar to permit the endwise removal of the latter, and releasable locking means to prevent the operation of said separating means.

4. In a typographical machine, the combination of a matrix magazine, a base frame upon which the magazine is removably mounted, an endwise removable escapement bar carried by said base frame in operative engagement with the magazine, means for

separating the magazine and escapement bar to permit the endwise removal of the latter, and releasable locking means to prevent the operation of said separating means at certain times and to lock the matrices in the magazine at other times.

5. In a typographical machine, the combination of a matrix magazine, a base frame upon which the magazine is removably mounted, an endwise removable escapement bar carried by said base frame in operative engagement with the magazine, means for separating the magazine and escapement bar to permit the endwise removal of the latter, and a removable locking rod which, in one position, prevents the operation of said separating means and, in another position, serves to lock the matrices in the magazine.

6. In a typographical machine, the combination of a plurality of matrix magazines, a shift frame in which the magazines are removably mounted, endwise removable escapement bars carried by the shift frame in operative engagement with the magazines, and means for disengaging the magazines from the escapement bars to permit the endwise removal of the latter preparatory to the removal of the magazines.

7. In a typographical machine, the combination of a matrix magazine, a base frame upon which the magazine is removably mounted, an endwise removable escapement bar carried by said base frame, a magazine retaining member hinged to the base frame, and means cooperating with said member for raising the magazine above the escapement bar to permit the endwise removal of the latter preparatory to the removal of the magazine.

8. In a typographical machine, the combination of a removable matrix magazine, a separate base frame therefor provided with a movable magazine retaining member, an endwise removable escapement bar carried by the base frame, and a hand operated rock shaft recessed to receive and cooperate with the magazine retaining member.

9. In a typographical machine, the combination of a magazine, a base frame upon which the magazine is removably mounted, an endwise removable escapement bar carried by the base frame, a retaining member hinged to the base frame and normally engaging the magazine, and a hand operated rock shaft journalled in the base frame and arranged to cooperate with said member for moving it into or out of operative position.

10. In a typographical machine, the combination of a plurality of matrix magazines, a shift frame wherein the magazines are supported, endwise removable escapement bars mounted in said frame, and means for separating the magazines and escapement bars to permit the endwise removal of the latter.

- 4
11. In a typographical machine, the combination of a plurality of matrix magazines, a shift frame wherein the magazines are removably supported, endwise removable escapement bars mounted in said frame and operatively engaged with the magazines, magazine retaining members hinged to the frame, and means cooperating with said members for disengaging the magazines from the escapement bars to permit the endwise removal of the latter preparatory to the removal of the magazines. 40
12. In a typographical machine, the combination of a plurality of matrix magazines, a shift frame wherein the magazines are removably supported, endwise removable escapement bars mounted in said frame and operatively engaged with the magazines, magazine retaining members hinged to the frame, and rock shafts arranged to cooperate with said members for disengaging the magazines from the escapement bars to permit the endwise removal of the latter preparatory to the removal of the magazines. 45
13. In a typographical machine equipped with assembling and distributing mechanisms, the combination of a plurality of magazines, a rigid supporting frame therefor shiftable to bring any magazine into operative relation to the assembling and distributing mechanisms, and means adjustably mounted in the framework of the machine for locating the said frame in its different operative positions. 50
14. In a typographical machine, the combination of a plurality of magazines, a shift frame wherein the magazines are mounted, a pair of locating bars arranged to cooperate with lugs on the shift frame, adjustable supporting brackets for the locating bars, and means for moving the latter into and out of operative position. 55
15. In a typographical machine, the combination of a shift frame comprising a bottom supporting frame and a plurality of subsidiary magazine frames arranged in superposed spaced relation and connected to the bottom frame, means for adjusting the subsidiary frames independently to set them in proper relation to the bottom frame, and means for locating the shift frame in different operative positions. 60
16. In a typographical machine, the combination of a plurality of matrix magazines, a shift frame comprising a bottom frame and a series of subsidiary magazine frames clamped thereto in superposed spaced relation and upon which the magazines are removably supported, and endwise removable escapement bars carried by the subsidiary frames and operatively engaged with the magazines. 65
17. In a typographical machine, a magazine shift frame comprising a bottom supporting frame and a plurality of superposed subsidiary magazine frames arranged in superposed spaced relation and clamped to the bottom frame, perpendicular guide members rising from opposite sides of the bottom frame, a series of adjusting screws located between said members and the sides of the subsidiary frames, and a corresponding series of adjusting screws located between the rear edge of said members and the subsidiary frames. 70
- 75
- In testimony whereof, I have affixed my signature hereto.

JAMES G. McNAMARA.
